UNITED STATES PATENT OFFICE.

JOHN C. MILLER, OF OAK PARK, ILLINOIS, ASSIGNOR TO SAMUEL S. OTIS.

TIME SWITCH.

Application filed December 24, 1925. Serial No. 77,496.

My invention relates, generally stated, to electrical time switches provided for the purpose of automatically arresting the flow of current to a circuit upon the lapsing of a predetermined length, or lengths, of time, and controllable to vary the length of time, at the will of the operator.

One of my objects is to provide a novel, simple and economical mechanism of the general character above stated whereby a switch controlled thereby may be caused, under the control of the operator, to automatically open after the lapsing of a selected period of time.

Another object is to provide a time element mechanism for use more particularly in connection with domestic electric toasters as commonly provided, to the end that the toaster will automatically cease to operate after a selected period of time has elapsed. Another object, and more particularly in this connection, is to provide a time device mechanism which may be used with a number of different kinds of electrical cooking devices as commonly provided and serve as a support therefor, with the manifest advantage.

Referring to the accompanying drawings:—

Figure 1 is a plan sectional view of mechanism constructed in accordance with my invention, the parts being shown in the position they assume when the switch of the device is in "off" position, the section being taken at the line 1—1 on Fig. 2 and viewed in the direction of the arrows. Figure 2 is a view in side elevation of the mechanism of Fig. 1 with a portion of the casing broken away; and Figure 3, an enlarged broken section taken at the irregular line 3—3 on Fig. 1 and viewed in the direction of the arrow.

Referring to the particular illustrated embodiment of my invention which is provided of a form particularly adapting it for use with an electric toaster such as commonly provided, it comprises a casing 10 shown as of general rectangular form and supported at its four corners on stub legs 11, the casing being shown as formed of a casting presenting the top plate 12 and the surrounding side walls 13, 14, 15 and 16, the bottom plate of the casing, and represented at 17, being shown as formed separately from the parts just described and secured in place in any suitable manner. The casing 10 at its opposite ends is provided with push plug electrical sockets 18 and 19 of any desirable con-

struction, such for example as those commonly used, the socket 18, by way of example, being adapted to connect with a push plug leading from the service line and the socket 19 being adapted for connection with a push plug which would be electrically connected with the electrical device to be controlled by the time mechanism located in the casing 10 and herein after described, and provided for the purpose of controlling the operation of a switch, as for example, that shown at 20 which is electrically connected with the terminals of both sockets 18 and 19, through wires 21 and 22, the wires 22 being broken away between their ends. The switch shown, the details of which are omitted because it is of a well known type, is of a construction involving a pair of push buttons 23 and 24 interlocked with each other whereby when one is pushed in the other is pushed out, the button 24 operating when pushed in to close the circuit between the sockets 18 and 19 and when moved outwardly by pushing in the button 23 to the position shown in the drawings, to break this circuit.

The time mechanism shown is provided for effecting the movement of the switch to "on" and "off" position and comprises a lever 25 fulcrumed at 26 on the casing 10 and pivotally connected at 27 with a bar 28 slideable in a guide 29 on the casing 10 and opposing at its outer end, the outer end of the push button 24, whereby when the lever 25 is rocked to the left in Fig. 1 it will push the button 24 in with the result of pushing the button 23 out, and thereby close the circuit between the sockets 18 and 19. A coil spring 30 surrounding the bar 28 bears at its opposite ends against the guide 29 and a stop 31 on this rod, serves to yieldingly hold the lever 25 in the position shown in the drawings and return it to this position when this lever is actuated to condition the time mechanism as herein after described, it being understood that upon swinging the lever 25 to the left in the drawing the flow of current will be established from the line to the electrical device connected up with the mechanism through the socket 19.

The opening of the circuit at the switch 20 is controlled through the medium of a device which is moved out of normal position upon actuating the lever 25 as stated either once or a plurality of times in succession, the amount of movement given this device depending upon the number of times

the lever is actuated, this device being automatically returnable to a position in which it actuates the switch 20 to shut off the current, following the lapsing of a predetermined period, or periods of time. The device just referred to, as shown, comprises a drum 32 rotatably mounted on a pin 33 carried by the top plate 12, this drum containing a coil spring 34 one end of which is connected with the pin 33 as represented at 35 and the other end of which is connected with the drum 32, as represented at 36, the tendency of this spring being to rotate the drum in counter-clockwise direction in 15 Fig. 1. The drum 32 is provided with a tappet 32^a into the path of movement of which a bar 23^a slidably mounted in brackets 10^a on the casing 10, extends, this bar being located in alignment with, and directly opposing, the push button 23, whereby this push button is pushed inwardly to break the circuit through the switch in the return of the drum 32 to the position shown in Fig. 1, under the action of the spring 34, following 20 the movement of this drum out of the normal position shown, in the manner herein-after described. The drum 32 is connected, as indicated at 37, with one end of a tape 38 which is partially wrapped about its periphery the other end of this tape being rigidly secured to, and partially wrapped about the periphery of, a second drum 39 journaled on a pin 40 carried by the plate 17, the drum 39 being formed with a sprocket portion 41, 25 connected, by means of a sprocket chain 42, with a sprocket wheel 43 journaled on a shaft 44 secured in the casing 10.

When the drum 39 is rotated in clockwise direction in Fig. 1 it draws upon the band 38 thereby rotating the drum 32 in clockwise direction in this figure against the resistance of the spring 34. The rotation of the drum 32 as just stated, is effected by mechanism carried by the lever 25 and comprising a stationary jaw 45 on this lever and a pivot jaw 46 provided on a finger-grip piece 47 pivoted on the lever as represented at 48. The jaw portions 45 and 46 are located at opposite sides of the sprocket chain 42, and 30 are adapted to grip this chain and move the latter, by the operator pressing to the left in Fig. 1 against the hand piece 47 which operates first to grip the sprocket between the jaws 45 and 46 and thereafter bodily swing 35 the lever 25 to the left in Fig. 1 and shift the sprocket chain accordingly, a stationary finger-grip 51 rigidly secured to the casing wall 15 forming a stop which may be engaged by a finger of the operator and permit 40 of a squeezing grip upon the handle 47.

It may be here stated that the swinging of the lever 25 to the left in Fig. 1 thus not only pushes in the switch button 24 to close the circuit between the sockets 18 and 19 45 and thus to the electrical device controlled

by the time mechanism, but also steps the drum 32 in clockwise direction withdrawing the stop 32^a from a position in which it obstructs the outward movement of the button 23, the switch remaining in closed position, 70 until the drum 32 reversely rotates, under the action of its spring 34 to a position wherein the push button 23 is pushed in and opens the same. The return movement of the drum 32 is timed to cause the switch 75 20 to remain closed for the desired predetermined length of time, the mechanism shown for this purpose comprising a device of the escapement type commonly employed in clocks and comprising a balance wheel 52 80 rotatably mounted on a shaft 53 carried by the casing 10, the coil spring cooperating with this balance wheel being represented at 54; and a ratchet 55 fixed on a shaft 56 mounted in the casing 10 and cooperating at 85 its escapement teeth with the escapement arms 57 and 58 carried by the balance wheel 52. The shaft 56 is provided with a pinion 59 which meshes with a gear 60 rotatably mounted on the hub portion 61 of the drum 90 39, this gear being provided with a pawl 62 pivotally mounted on a face thereof, as represented at 63 and yieldingly pressed, by a spring 64, in a direction to hold the pawl 95 in engagement with the teeth of a ratchet wheel 65 rigidly secured to the outer end of the hub 61. It will be understood from the foregoing that when the sprocket chain 42 is moved by the operator in actuating the lever 25, to move the drum 32 out of normal 100 position, the pawl 62 will idle as the ratchet 65 rotates in clockwise direction in Fig. 1, but will prevent reverse rotation of the ratchet 65, under the action of the spring 34, except at a predetermined speed controlled 105 by the escapement device referred to, by reason of its gear connection with the pawl-equipped gear 60.

The setting up of the drum 32 out of normal position by actuating the lever 25 110 without affecting the escapement mechanism, permits the operator to successively actuate this lever a plurality of times, whereby the point to which the tappet 32^a is moved out of normal position may be controlled by the 115 operator, requiring a greater or less time, as the case may be, for the return of this tappet to switch-opening position. Thus, by way of example, the parts may be so constructed and arranged that a single actuation of the lever 25 requires the lapse of a minute of time before the drum 32 will have returned automatically to a position in which the push button 23 is forced to 120 switch-opening position, and that each subsequent actuation of the lever thereafter prolongs for one minute the opening of the circuit of the switch 20. Therefore, the operator by actuating the lever 25 say, for example, three times, the lever automatically 125 130

returning to the position shown in Fig. 1 after each operation, steps up the drum 32 to such a position that it requires the lapsing of three minutes before the tappet 32^a, 5 driven by the spring 34, under the control of the escapement mechanism, reaches a position in which the push button 23 is moved to "off" position.

As a means of signalling the operator, upon 10 the opening of the switch 20, I provide a bell 66 secured to the casing 10 and with which a clapper 67 cooperates, this clapper being carried by a lever 68 fulcrumed at 69 on the casing and extending at one end into the 15 path of movement of the push button 24, so that when the push button 23 is pushed in and the push button 24 is pushed out the bell 66 will be automatically sounded.

The mechanism is also adapted to permit 20 of the maintaining of the circuit closed through the switch 20 for an indefinite time, as by the provision of means for holding the lever 25 in the position to which the operator swings it for pushing the button 24 25 in. By way of example the catch device shown at 70 may be provided, this device being pivoted at 71 on the wall 15 of the casing 10 and having a shoulder portion 72 for interlocking with the finger portion 47 30 of the lever 25 when the latter is operated as stated, this catch being manually movable into and out of locking position.

The particular illustrated embodiment of 35 my invention is adapted particularly for use with certain cooking devices, as for example toasters, which latter may be set into the dished top of the casing 10, producing a very compact and desirable construction and rendering cooking devices already in use, 40 automatically controllable for predetermined timed operation.

While I have illustrated and described 45 my invention as embodied in a particular construction of device, I do not wish to be understood as intending to limit it thereto, as the same may be variously modified and altered without departing from the spirit 50 of my invention.

What I claim as new, and desire to secure by Letters Patent, is:

1. Mechanism of the character described comprising a controlling element, a movable member controlling one position of said element, means controlling another position of 55 said element, said means being movable out of normal position under the control of said movable member, and time mechanism controlling the return of said means to normal position.

2. Mechanism of the character described comprising a controlling element, a movable member controlling one position of said element, means controlling another position of 60 said element, said means being movable out of normal position under the control of said

movable member in the movement of the latter to a position in which it controls said element, and time mechanism controlling the return of said means to normal position.

3. Mechanism of the character described 70 comprising a controlling element, means controlling the position of said element, a movable member, means actuated by said movable member for moving said first-named means out of normal position and 75 constructed and arranged to cumulate the movements of the latter in one direction in successive actuations of said member, and time mechanism controlling the return of said first-named means to normal position 80 and operative to effect such return upon the lapsing of a predetermined interval of time of a length dependent on the number of actuations of said member.

4. Mechanism of the character described 85 comprising a controlling element, a movable member controlling the position of said element, means also controlling the position of said element, means actuated by said movable member for moving said first-named 90 means out of normal position and constructed and arranged to cumulate the movements of the latter in one direction in successive actuations of said member, and time mechanism controlling the return of said first-named means to normal position and operative to effect such return upon the lapsing of a predetermined interval of time of a length dependent on the number of actuations of said member. 100

5. Mechanism of the character described comprising a controlling element, a movable member controlling the position of said element, means also controlling the position of said element, means actuated by said movable member in the movement of the latter to a position in which it controls said element for moving said first-named means out of normal position and constructed and arranged to cumulate the movements of the latter in one direction in successive actuations of said member, and time mechanism controlling the return of said first-named means to normal position and operative to effect such return upon the lapsing of a predetermined interval of time of a length dependent on the number of actuations of said member. 105

6. Mechanism of the character described comprising a controlling element, means controlling the position of said element and tending to move to such controlling position, a member movable relative to said means, means actuated by said movable member for moving said first-named means out of normal position, and time mechanism controlling the return of said first-named means to normal position. 110 120

7. Mechanism of the character described comprising a controlling element, means con- 130

trolling the position of said element and movable element operating when moved in one direction to engage one of said first-referred-to elements, a second member movable to actuate the other of said first-referred-to elements, means actuated by said first-named member for moving said second-named member out of normal position and constructed and arranged to cumulate the movements of the latter in one direction in successive actuations of said first-named member, and time mechanism controlling the return of said second-named member to normal position. 75

10 means to normal position and operative to effect such return upon the lapsing of a predetermined interval of time of a length dependent on the number of actuations of said member.

15 8. Mechanism of the character described comprising a controlling element, a movable member controlling the position of said element, means also controlling the position of said element and tending to move to such 80 controlling position, means actuated by said movable member for moving said first-named means out of normal position and constructed and arranged to cumulate the movements of the latter in one direction in successive operations of said member, and time mechanism controlling the return of said first-named means to normal position and operative to effect such return upon the lapsing of a predetermined interval of time of a length dependent on the number of actuation of said member. 85

9. Mechanism of the character described comprising a controlling element, means controlling the position of said element and 90 comprising a rotatable member tending to rotate to such controlling position, a movable member, means actuated by said movable member for moving said rotatable member out of normal position and comprising a flexible member engaging said rotatable member, and time mechanism operatively engaging said flexible member and controlling the return of said rotatable member to normal position and operative to effect such return upon the lapsing of a predetermined interval of time of a length dependent on the number of actuations of said member. 95

10. In combination with mechanism having controlling elements movable in opposite directions, of mechanisms for controlling said first-named mechanism comprising a movable element operating when moved in one direction to engage one of said first-referred-to elements, a second member movable to actuate the other of said first-referred-to elements, means actuated by said first-named member for moving said second-named member out of normal position, and time mechanism controlling the return of said second-named member to normal position. 105

11. In combination with mechanism having controlling elements movable in opposite directions, of mechanisms for controlling said first-named mechanism comprising a

12. Mechanism of the character described comprising a controlling mechanism having controlling elements movable in opposite directions, a pivoted lever cooperating with one of said elements and operating when moved in one direction to actuate said element, a rotatably supported drum, a spring tending to rotate said drum in one direction, means whereby said drum upon reaching a predetermined position in operating, as stated, actuates the other of said controlling elements, a flexible element engaging the periphery of said drum and cooperating when drawn upon to move said drum out of normal position, a second drum engaging the free end of said flexible element, means actuated by said lever for rotating said second drum, and time mechanism operatively engaging said flexible element and controlling the return of said drum to normal position. 90

13. Mechanism of the character described comprising a controlling mechanism having controlling elements movable in opposite directions, a pivoted lever cooperating with one of said elements and operating when moved in one direction to actuate said element, a rotatably supported drum, a spring tending to rotate said drum in one direction, means whereby said drum upon reaching a predetermined position in operating, as stated, actuates the other of said controlling elements, a flexible element engaging the periphery of said drum and operating when drawn upon to move said drum out of normal position, a second drum engaging the free end of said flexible element, means actuated by said lever for rotating said second drum, and comprising a suitably supported endless drive element operatively engaging said drum and means on said lever operating when the latter is moved in one direction to actuate said endless element and when actuated in the opposite direction to idle relative to said element, and time mechanism controlling the return of said drum to normal position. 110

14. In combination with an electric switch having controlling elements movable in opposite directions, a movable member engaging one of said elements, means for engaging the other of said elements and movable out of normal position under the control of said 125

movable member, and time mechanism controlling the return of said first-named means to normal position.

15. In combination with an electric switch having controlling elements movable in opposite directions, a movable member engaging one of said elements, means for engaging the other of said elements and movable out of normal position under the control of 5 said movable member in the movement of the latter to a position in which said member operates the one of said controlling elements with which it cooperates, and time mechanism controlling the return of said 10 first-named means to normal position.

16. Mechanism of the character described comprising a controlling element, movable means adapted, in their movement to normal position, to engage said element and force 20 it into a certain position, a movable member, means actuated by said movable member for moving said first-named means out of normal position and comprising a flexible member engaging said first-named means, and 25 time mechanism operatively engaging said flexible member and controlling the return of said first-named means to normal position.

17. Mechanism of the character described comprising a controlling element, movable means adapted, in their movement to normal position, to engage said element and force it into a certain position comprising a rotatable member tending to rotate to normal 30 position, a movable member, means actuated by said movable member for moving said rotatable member out of normal position and comprising a flexible member engaging 35 said rotatable member, and time mechanism operatively engaging said flexible member and controlling the return of said rotatable member to normal position.

18. Mechanism of the character described comprising a controlling element, movable 45 means adapted in their movement to normal position to engage said element and force it into a certain position, a movable member, means actuated by said movable member for moving said first-named means out of normal 50 position and constructed and arranged to cumulate the movements of the latter in one direction in successive operations of said member and comprising a flexible member engaging said movable means, and time mechanism controlling the return of said 55 first-named means to normal position.

19. Mechanism of the character described comprising a controlling element, means controlling the position of said element and

movable into and out of a position in which 60 said element is in a certain position, means operative in successive movements thereof to effect intermittent, successive, cumulative movements of said first-named means out of 65 said position and time mechanism controlling the return of said first-named means to normal position and operative to effect such return upon the lapsing of a predetermined interval of time of a length dependent on the number of actuations of said last-named 70 means.

20. Mechanism of the character described comprising a controlling element, means controlling the position of said element and movable into and out of a position in which 75 said element is in a certain position, means movable relative to said first-named means and operative in successive movements thereof to effect intermittent, successive, cumulative movements of said first-named means 80 out of said position and time mechanism controlling the return of said first-named means to normal position and operative to effect such return upon the lapsing of a predetermined interval of time of a length dependent on the number of actuations of said 85 last-named means.

21. Mechanism of the character described comprising an electric switch, a movable member operative to force said switch to 90 closed position, means controlling the opening of said switch and movable out of switch-opening position under the control of said movable member in moving to switch-closing position, and time mechanism controlling the return of said first-named means 95 to normal position.

22. A combined time mechanism and utensil supporting structure comprising in combination, a casing including a supporting 100 element, side walls and an upper wall comprising a flat plate adapted to serve as a support for utensils the action of which is controlled by mechanism housed in said casing, time switch mechanism housed in said 105 casing comprising a switch and time mechanism controlling said switch operating automatically to open said switch a predetermined time after its closure, means projecting through one of said side walls to close 110 said switch and initiate action of said time mechanism, means carried by said casing to electrically connect said switch to the plug of an electrical utensil supported on said plate, and means carried by said casing for 115 connecting the switch to a source of energy.

JOHN C. MILLER.
